UNITED STATES PATENT OFFICE.

ALBERT ALBERTSON, OF JERSEY CITY, NEW JERSEY, ASSIGNOR TO JOHN MATTHEWS, OF NEW YORK, N. Y.

BOTTLE-STOPPER.

SPECIFICATION forming part of Letters Patent No. 231,518, dated August 24, 1880.

Application filed April 21, 1880. (No model.)

To all whom it may concern:

Be it known that I, ALBERT ALBERTSON, of Jersey City, in the county of Hudson and State of New Jersey, have invented a new and Improved Bottle-Stopper, (Case D,) of which the following is a specification.

My invention relates to improvements in that class of bottle-stoppers which are connected with the bottle outside of the mouth of the same.

The invention consists in combining a yielding bottle-stopper having metal cap and transverse pivots with the mouth of the bottle by upright posts rigidly secured to the neck-band of the bottle, the upper ends of which posts are provided with angular or bent slots, through which the said pivots are passed, all as herein-after more fully described.

In the accompanying drawings, Figure 1 represents a top view of a bottle provided with the improved stopper; Fig. 2, a front elevation of the same; Fig. 3, a side elevation, and Fig. 4 a vertical cross-section taken on line *k k* of Fig. 1.

Referring to the drawings, D represents a bottle-stopper having a cup-shaped body and a flange, *d*, and an upright projection inclosed in a metal cap or case, *m*. The cup-shaped lower portion is open at the lower end.

To opposite sides of the head of the bottle are applied upright posts *G G*, the lower ends whereof are fastened to the collar *n*, that is placed around the neck of the bottle. The upper parts of the posts *G* may be strengthened by a band, *o*, bent in against the head of the bottle on both sides of the posts, and secured to the latter. The upper ends of the posts *G* project some distance above the mouth of the bottle, and are provided with wings or projections *p p*, in each of which is a curved slot having two parts, *q* and *s*, at angles to each other.

Through the metal cap or case *m* a diametrical pin, *t*, is passed horizontally, and the projecting ends of said pin are passed through the slots *q q* in the projections *p p*, and provided with heads to prevent the pins from

slipping out and the stopper from losing its pivotal connection with the posts *G G*.

To open the bottle it is necessary to press against the side of the metal cap *m*, by which movement the ends of the pin *t* are forced out of the parts *s* to the parts *q* of the slots, thereby raising the stopper partly out of the bottle, and finally turning it on its side at about right angles to the head of the bottle, as indicated by dotted lines in Fig. 4.

To close the bottle the stopper is pushed in a direction opposite to that just described until the flange *d* comes in contact with the rim of the bottle and arrests the further lateral movement of the stopper and causes it to turn over and enter the mouth of the bottle and close it.

It will be seen that the only connection between the elastic stopper and the supporting collar is one single pivotal connection, the pivot passing through angular slots in the wings of the posts.

By making the stopper *D* cup-shaped and placing it in the mouth of the bottle in an inverted position a very tight connection is made between the stopper and the mouth of the bottle, and as the stopper is very elastic, in case an aerated liquid is placed in the bottle the pressure will expand the sides of the stopper and press them closely and tightly against the sides of the mouth.

I claim—

The posts *G G*, fixed rigidly to the neck-band of the bottle and provided with the slotted wings *p* at the upper ends, in combination with a flexible bottle-stopper having metal cap *m* and transverse pivots *t*, so that said pins travel in the slots of the immovable wings *p* in opening and closing the stopper, substantially as herein shown and described.

This specification of my invention signed by me this 28th day of February, 1880.

ALBERT ALBERTSON.
